REMEDIAL FOOTWEAR

La Porte Van Sant, Chicago, Ill.

Application July 25, 1933, Serial No. 682,146
Renewed April 20, 1936

3 Claims. (Cl. 36—71)

This invention relates to certain novel improvements in remedial footwear, and has for its principal object the provision of an improved construction of this character which will be highly efficient in use and economical in manufacture.

Another object of this invention is to provide a new article of footwear in the form of a device for alleviating and remedying diseased areas and conditions of the human foot such as are caused, for example, by corns, callouses, and the like.

Another object of the invention is to provide a new article of footwear for alleviating corns, callouses, and the like by diverting the weight of the body off the diseased area and onto the healthy area of the foot.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a top plan view showing the new device with the parts thereof assembled;

Fig. 2 is a longitudinal sectional view on line 2—2 in Fig. 1;

Fig. 3 is a fragmentary longitudinal sectional view on line 3—3 in Fig. 1;

Figs. 4, 5, and 6 are perspective detail views of the several inserts embodied in the invention; and

Fig. 7 is a perspective view showing the insole and subsole embodied in the device.

A preferred embodiment of the new device is shown in the drawing and includes a flexible subsole 10, which may be made of leather, fiber, or the like, and is adapted to be inserted into an article of footwear, such as 11.

The new device also includes an insole 12, which may be made of fiber, leather, or the like. This insole 12 is attached to the upper side of the subsole 10 by means of a tongue 13 which is cut out of the toe portion of the insole 12 and which is adhesively or otherwise secured to the upper side of the subsole 10; thereby providing a cut-out or recessed area 14 in the toe portion of the insole 12.

This recessed or cut-out area 14 is adapted to receive, or for arrangement below, the diseased area of the foot, such as a callous or corn, or the like, and when such diseased area is disposed in the cut-out portion 14 the weight of the body is thrown off the diseased area of the foot and onto the healthy area or bottom surface of the foot, which latter area is distributed over the

entire area of the upper surface of the insole 12 excepting the cut-out area 14. In this manner the pain incidental to pressure on the diseased area is relieved and the diseased condition in time remedied.

By the same principle of alleviating and remedying the diseased foot condition by throwing the weight of the body off from the diseased area onto the healthy area of the foot, a diseased condition such as, for example, a corn or a callous on the bottom of the great toe, may be remedied by providing a cut-out portion 15 in the toe portion of the insole 12 and by adhesively or otherwise attaching the tongue 16 formed by such cut-out portion to the subsole 10 which is shorter in length than the insole 12 and extends over about three-fourths of the length of the insole 12; the subsole 10 ending rearwardly of the front end or toe portion of the insole 12.

The new device also includes a series of inserts 17, 18, and 19, each of which is longer than the other, in the order named. Inserts 17 and 19 may be detachably attached to the subsole 10 and adjustably positioned thereon between the insole 12 and the subsole 10 by means of separable fasteners each including a male element 20 attached to the insert and a female element 21 attached to the insole or vice versa.

The insert 18 has female fastener elements 22 attached thereto so that it may be inserted between the inserts 17 and 19 if desired; in which event the male fastening elements 20 on the insert 17 are secured to the female fastening elements 22 on the insert 18.

Each of the inserts 17, 18, and 19 has a cut-out portion 23 formed in the toe portion by inwardly recessing the transverse front edge 24 thereof. In use, these cut-out portions 23 are registered or aligned with the cut-out portion 14 below the diseased area of the foot.

If desired a portion of one or both side edges of the combined insole 12, subsole 10, and inserts 17, 18 and 19, may be recessed, as at 25, so as to alleviate pressure on a diseased area of the foot, such as a corn, at that point.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I

claim as new and desire to protect by Letters Patent is:

1. A remedial device for insertion into an article of footwear, comprising a flexible subsole and a flexible insole for attachment to the upper side of the subsole; said insole having a cut-out portion providing a recess adapted to receive a dis-eased area of the foot and said cut-out portion providing a tongue attached to the said subsole; 5 said device including an insert arranged between the said subsole and the said insole and including a toe-portion having a portion cut out of its transverse front edge providing a recess, and said recess being registered with the first named recess; and means for detachably attaching the said insert to, and for adjustably positioning the same on, the said subsole. 10
2. A remedial device for insertion into an article of footwear, comprising a flexible subsole and a flexible insole for attachment to the upper side of the subsole; said insole having a cut-out portion providing a recess adapted to receive a dis-eased area of the foot and said cut-out portion providing a tongue attached to the said subsole; 15 said device including a series of inserts arranged between the said insole and the said subsole and each of said inserts having a portion cut out of its transverse front edge providing a recess and said recesses being registered with the first- 20 named recess.
